UNITED STATES PATENT OFFICE

2,031,892

MEDICINE GLASS COVER

Edward Johnson, Montclair, N. J., assignor to
 Meinecke & Company, New York, N. Y., a corporation of New Jersey

Application May 3, 1935, Serial No. 19,650

4 Claims. (CL 65—16)

My invention relates to a new and improved medicine glass cover and more particularly to means connected with the cover for indicating not only the patient's name, but the kind of 5 medicine and the time of taking the medicine for each patient.

The invention is an improvement upon that described and claimed in my Patent No. 1,920,396.

While the invention shown and covered in that 10 patent has met with very substantial commercial success, it did not fully meet all the requirements of hospitals, which are more fully hereinafter referred to.

It is now the practice in most hospitals 15 the medicinal prescriptions for the various patients to be made up in what is known as a hospital drug room and these prescriptions are then kept in a medicine closet on each floor of the hospital.

20 At the various times when patients are to be given their medicines, the desired dose is poured into a medicine tumbler, or when the medicine is in the form of pills or capsules, it may be placed in the depressed part of the cover, as 25 shown in this application and in my prior patent. The tumblers are then placed on a tray with a number of other tumblers for different patients. According to the methods now used in most hospitals, in order to identify each patient's tumbler, 30 a card with the patient's name and room or ward number and instructions for taking the medicine written thereon is placed either under the tumbler or on top of it.

If the card is placed on the top of the tumbler, 35 the cards are liable to fall off while the tray is being carried from one room to another or from one patient's bed to another. Sometimes these cards, that have fallen off, are placed on the wrong tumblers and sometimes with serious 40 results. If the cards are placed under the tumblers, the names cannot be read and, furthermore, occasionally the liquid spills over the tumbler so that the card becomes soiled, making it necessary to write up a new card.

45 Most hospitals have now adopted a plan of having color charts to indicate the type of medicine or the proper or approximate time for giving such medicine to each patient. For instance, a red card may indicate medicines to relieve pain and induce sleep, and such medicine is to be given at once. A blue card may indicate medicine to be administered twice a day. A green card may indicate medicine to be given four times a 50 day. A yellow card may indicate medicines to

be given before meals. It is understood that each color may indicate a different time or hour when the medicine has to be given, or, in some cases, 5 may indicate a special kind of medicine. In some hospitals as many as nine or ten colors are used. These colors cannot be considered standard because most hospitals establish their own particular set of color charts, depending upon the size 10 of the hospital and the character of the patients admitted.

When preparing medicines, a small colored 15 identification card is used with the name of the patient or room number and this small colored identification card must correspond with the official color chart adopted by the hospital so that 20 nurses can tell at a glance just when and how often the medicine is to be given.

The object of the present invention is to provide 25 a safe method for having the cards with the name of the patient or room number and instructions for taking the medicine retained on the tumblers to which they belong and at the same time keep the written matter on the card plainly in view.

A further object of the invention is to permit 25 the cards containing the matter above mentioned to be made of different colored paper or cardboard, which colors correspond with the colors on a chart kept in the hospital room.

My invention consists essentially of a cover 30 which fits over the top edge of a medicine tumbler and is securely held thereon by a dependent flange or side of the cover which surrounds the greater part of the cover and also surrounds the greater part of the tumbler. The said cover has 35 means, preferably formed integral therewith, for holding the colored card with the patient's name, etc., which belongs to the respective tumbler.

In addition, the cover has a depression or 40 depressions in the top thereof for holding medicinal pills, whenever medicine is to be given to the patient in that form, or in conjunction with the liquid contents of the tumbler.

The device is usually made of metal, but it 45 will be understood that any suitable material can be used.

The invention is illustrated in the following drawing in which:

Fig. 1 is a plan view of the invention; 50
 Fig. 2 is a cross sectional view of the tumbler cover taken on the line 5—5 of Fig. 1;

Fig. 3 is a perspective view of a medicine tumbler with the cover thereon; and

Fig. 4 is a top plan view of the tumbler cover having a card secured thereon, the dotted lines 55

showing the outline of the portion of the device covered by the card.

The device consists preferably of a sheet of metal 6 having a depression 7 stamped in the center thereof. The top of the member 6 is extended for a distance of approximately one quarter of the circumference of the tumbler, as shown at 8. On the extended portion 8 a pair of clips 9 are either stamped out of or secured to the top of the member 8 to permit the insertion of a card 10 of any desired color, as shown in Fig. 4. The cover has a depending flange 11 shown more clearly in Figs. 2 and 3, which fits over the top of the tumbler and holds the cover in place.

15 While the card holding members 9 are shown in the drawing as being stamped out and rising up from the member 8, in the form of a clip, it will be understood that other card holding means could be formed on the cover. The card holding means could also be formed by bending the front part of the extending member 8 back upon itself to permit the insertion and holding of a card. While I have shown the extension 8 as being formed integral with the medicine tumbler cover, it will be understood that it could be made, if desired, of a separate piece of metal to be secured or attached to the medicine cover itself.

I claim:

1. A medicine glass cover comprising a plate 30 having a central depression adapted to seat within a glass and forming a receptacle for medicines, a depending flange extending around a portion of the periphery thereof and cooperating with the walls of said central depression to form a groove 35 adapted to receive the upper edge of the glass, an extension of said plate between the ends of said depending flange projecting beyond the sides of the glass, and clips carried by said extension adapted to receive the edge of a card to hold the 40 card in position over the plate whereby the insignia on said card are visible and whereby said card serves as a cover for said depression.

2. A medicine glass cover comprising a metal plate having a central depression adapted to seat within a glass and forming a receptacle for medicines, a depending flange extending around a portion of the periphery thereof and cooperating with the walls of said central depression to form a groove 5 adapted to receive the upper edge of the glass, an extension of said plate between the ends of said depending flange projecting beyond the sides of the glass, and clips stamped out of said 10 extension adapted to receive the edge of a card to hold the card in position over the plate whereby the insignia on said card are visible and whereby said card serves as a cover for said depression.

3. A medicine glass cover comprising a plate having a central depression adapted to seat within a glass and forming a receptacle for medicines, a depending flange extending around a portion of the periphery thereof and cooperating with the 20 walls of said central depression to form a groove adapted to receive the upper edge of the glass and card-holding means formed integrally with said cover between the ends of said depending flange, said means projecting above the top surface of said cover to engage the edge of the card 25 so as to hold the card in place over the cover without concealing the insignia on said card.

4. A medicine glass cover comprising a plate having a central depression adapted to seat within 30 a glass and forming a receptacle for medicines, a depending flange extending around a portion of the periphery thereof and cooperating with the walls of said central depression to form a groove 35 adapted to receive the upper edge of the glass and clip means formed integrally with said cover between the ends of said depending flange and bent upwardly above the top surface of said cover so as to engage and hold a card in position over the cover without concealing the insignia on 40 said card.

EDWARD JOHNSON.
